TABLE AND FLOOR LAMP KNOB SWITCH

Howard T. Thornton and Carl A. Sjoquist,
Cranston, R. I.

Application August 31, 1951, Serial No. 244,593

1 Claim. (Cl. 240—123)

1

This invention relates to table and floor lamps of the type having a plurality of light bulbs in a shade or the like and of the type wherein the shade is suspended from the upper end of a pedestal, and in particular this invention includes a lamp of this type having switch elements incorporated in a housing at the upper end of the pedestal and from which the shade is suspended and wherein the switch elements are actuated by a knob positioned on the end of the pedestal and on the outside of the shade.

The purpose of this invention is to provide an improved switch for table and floor lamps wherein the switch is positioned so that it is not necessary to reach in under a shade to light or extinguish lamps positioned below the shade.

In the conventional type of table and floor lamp switches are provided in light sockets positioned around the upper end of a pedestal and even though combination switches are used in some lamps it is necessary to reach in under the shade in order to operate the switch. With this thought in mind this invention contemplates a switch positioned in a lamp mounting housing at the end of a pedestal and from which a lamp shade is suspended, in which the switch is provided with an actuating knob that replaces the conventional ornament positioned on the outside of the lamp shade and on the upper end of the pedestal so that the switch may be actuated without reaching in under the lamp shade.

The object of this invention is, therefore, to provide means for forming a switch for table and floor lamps whereby the switch is operated on the outside of a shade surrounding a plurality of lamp bulbs.

Another object of the invention is to provide a combination switch for table and floor lamps having depending shades which is operated by a knob extended above the shade and in which the electric cord may extend through the pedestal or through an opening in the switch housing positioned in the lamp shade and on the upper end of the pedestal.

A further object of the invention is to provide an improved table or floor lamp having a combination switch operated by a knob extended beyond a shade of the lamp, which is of a simple and economical construction.

With these and other objects and advantages in view the invention embodies a lamp having a switch housing positioned on the upper end of a pedestal with a shade suspended from the housing and having contact points connected in circuits to the lamp and positioned in the

2

housing and a rotor with a segment thereon for completing circuits to the lamp as the rotor is rotated by a knob extended from the upper end of the pedestal and positioned above the lamp shade suspended on the housing.

Other features and advantages of the invention will appear from the following description taken in connection with the drawings wherein:

Figure 1 is a side elevational view showing a 10 table lamp in which the supply cord extends through a pedestal thereof and in which parts are broken away and shown in section.

Figure 2 is a detail looking upwardly toward the under surface of the switch housing mounted 15 on the upper end of the pedestal and showing a plurality of lamp sockets extended therefrom.

Figure 3 is a plan view showing the knob on the upper end of the switch housing and showing the shade with parts thereof broken away.

Figure 4 is a vertical section through the switch 20 housing illustrating a modification wherein the electric supply wires extend through an opening in one side of the switch housing.

Figure 5 is a detail showing a section through 25 part of the switch housing and illustrating the method of mounting the lamp socket in the housing.

Figure 6 is a plan view showing the opening in the shell of the light socket.

Figure 7 is a vertical section through a portion 30 of the switch housing of the design shown in Figure 1 wherein the supply wires extend through the pedestal.

Figure 8 is a detail showing a sectional plan 35 through the wire holding element in the lower part of the switch housing.

Figure 9 is a plan view of the switch housing shown in Figure 4 with the cover plate omitted.

Figure 10 is a similar view showing the contact 40 segments positioned above the wire holding ring shown in Figure 9.

Figure 11 is a view showing a wiring diagram with the cam segment positioned to complete circuits to all of the lights of the lamp.

Figure 12 is a similar view showing a wiring diagram with the parts positioned whereby a circuit is completed to only one light of the lamp.

Referring now to the drawings wherein like 50 reference characters denote corresponding parts the improved lamp switch of this invention includes a housing 10 positioned on the upper end of a tubular section 11 of a pedestal 12, a knob 13 for turning the stem 14 in the housing 10 and on which segments 15 are provided which

engage contact arms 16 mounted on the base 17 of the housing.

In this design the pedestal is provided with an inner tube 18 and the base 17 of the housing 10 is journaled on a collar 19 threaded on the upper end of the tube 18. The lamps are supplied with current through wires 20 and 21 which extend upwardly through the tube 18 and with one of the wires, such as the wire 20 connected to a lower ring 22, and the other wire 21 connected to the segment 15 a circuit may be completed through lights 23 extended from sockets 24 in the outer surface of the housing.

The housing may be provided with a contact, such as the contact 16 for each lamp and the cam 15 is positioned to engage one, two, or all of the contacts. The contacts 16 are secured to the base 17 of the housing by screws 25, as shown in Figure 7 and a member 28a of the base 17, positioned below the stem 14 is provided with laterally disposed openings 26 and 27 through which the wires 20 and 21 extend.

The housing 10 is provided with a cover plate 28 and the knob 13 is secured in position with arcuate plates 29 and 30 that extend into an annular recess 31a at the base of the knob, as shown in Figure 3. The plates 29 and 30 are secured to the cover 28 by screws 31 and 32 and the cover plate may be secured to the base or wall of the housing by screws 33.

In this design the lamp is provided with a shade 34 that is secured to a flange extended around the cover plate 28 by screws 33.

The inner tube 18 is secured to the upper end of a tube 36 by a coupling 37, the coupling being threaded on the upper end of the tube 36 and also threaded on the lower end of the tube 18. A nut 38 is provided on the lower end of the tube 36 by which the tube is secured in the pedestal of the lamp.

The light cord including the wires 20 and 21 extends through a laterally disposed opening 39 in the base of the pedestal and a plug 40 is provided on the outer end of the cord.

In the design illustrated in Figures 4, 9 and 10 the lamp is provided with a switch housing 41 having a base 42, a cover plate 43 and a knob 44. In this design an electric cord including wires 45 and 46 extends through an opening 47 in one side of the housing and the wire 45 is connected to a terminal 48 of a ring 49 whereas the other wire 46 is connected by bolts 50, 51 and 52 to shells 53 of the light sockets 54.

As shown in Figure 9 the wire 45 is connected to the terminal 48 of a ring 49 and with the parts positioned as shown in Figure 4 the ring 55a on which cams 55 and 56 are positioned is mounted in a recess 57 on the lower part of a stem 58 that extends from the knob 44 and with the ring 49 in engagement with the ring 55a the circuit is established from the wire 46 through the rings 49 and 55a to contacts 58, 59 and 60 that extend upwardly from the base 42 on which the contacts are mounted by screws 61, 62 and 63 which extend through flanges 64, 65 and 66, respectively on the lower ends of the contacts.

As shown in Figure 9 the contact 58 is connected by a wire 67 to a terminal 68 from which a brush 69 extends and, as shown in Figure 4 the brush 69 engages a center terminal 70 of the base 71 of a light bulb 72. The contact 59 is connected to the terminal 73 by a wire 74 and a brush 75 extended from the terminal 73 is also positioned to contact the center terminal of the base of a light bulb. The contact 60 is con-

nected by a wire 76 to a terminal 77 by a brush 78 and the brush 78 is positioned to engage the center terminal of the base of a light bulb.

It will be understood that any suitable number of light bulbs, sockets, therefor, and contacts may be provided in the switch housing.

In this design the switch housing is positioned on the upper end of a tube 79, similar to the tube 11 and an inner tube 80 on which a collar 81 is threaded is positioned in the tube 79 to provide mounting means for the switch housing.

The knob 44 is also provided with an annular recess 82 similar to the recess 31 on the knob 13 and arcuate plates 83 and 84 which are secured to the cover plate 43 by screws 85 extend into the recess 82 to hold the knob 44 in position with an extension 86 on the lower end extended into an opening 87 in the center of the base of the housing.

The housing of this design is also provided with an opening 88 through which wires may be placed should it be desired to bring supply wires through the center of the pedestal.

It will be understood that the lamp structure is the same in both designs, the only difference being in the fact that the wires extend through the pedestal and through an opening 39 in one side of the base in one design and through an opening 47 in the switch housing in the other design.

The cams 55 and 56, which are carried by the stem of the knob 44 are rotated by the knob to make or break the circuit, and in the diagram illustrated in Figure 12 one of the cams 55 is shown in engagement with the contact 58 whereby the circuit to one light as indicated by the numeral 90 is completed and with continued movement of the cam or segment 55 until the segment engages the contact 59 the circuit to a light 91 would be completed and with still further movement of the segment by the knob the segment would engage the contact 60 whereby circuits to the three lights 90, 91 and 92 would be completed. The terminals of the lamps are connected to a source of current supply by a wire 93 at one side and a wire 94, which is connected to the terminal 48 completes the other side of the circuit through the ring 49, segments 56 and contacts 58, 59 and 60.

The circuits to the lights are completed, therefore, by turning the knobs 13 or 44 and a circuit may be completed to one light as shown in Figure 12 or to all three lights as shown in Figure 11, or to any suitable number of lights as may be desired.

It will be understood that other modifications may be made in the design and arrangement of the parts without departing from the spirit of the invention.

What is claimed is:

In a lamp, a switch housing provided with an open top and an opening in one side thereof and having a base, a cover plate mounted on said switch housing to close the open top thereof, a knob positioned above said plate and including a stem portion, an electric cord including wires extending through said opening, a first vertically disposed tube extending downwardly from said housing, a second tube arranged within said first tube, a collar threadedly engaging said second tube and engaging said base, said knob being provided with an annular recess, an annular clamp seated in said recess and connected to the upper surface of said cover plate, an extension projecting downwardly from said knob, there be-

ing an opening arranged centrally in said base for rotatably receiving said extension, a plurality of light sockets extending from said base, a first ring connected to said base and having a terminal electrically connected to one of said wires, securing elements connecting said other wire to said light sockets, a second ring slidably connected to the first ring and to the stem portion of said knob and provided with opposed cams for selectively completing the circuit to said sockets upon 10 manual rotation of said knob.
